SNOWMOBILE TOOL

Howard A. Fistler, Utica, and Richard A. Hollingsworth,
Mount Clemens, Mich., assignors to HFCO, Mount
Clemens, Mich.

Filed Feb. 28, 1972, Ser. No. 230,202

Term of patent 14 years

Int. Cl. D8—05

U.S. Cl. D8—26

FIG - 3

FIG - 2

FIG - 1

FIG - 4

FIG - 5

FIGS. 1, 2 and 3 are, respectively, side, elevational, bottom and top plan views of a snowmobile tool embodying our design;

FIG. 4 and 5 are opposite end elevational views of said snowmobile tool; said FIGS. 4 and 5 being as viewed in the direction of the arrows 4—4 and 5—5, respectively, shown in FIG. 1.

One end of the snowmobile tool changes the drive belt on a snowmobile by spreading apart the pulley halves and the other end thereof changes spark plugs on a snowmobile by wrenching them.

We claim:

The ornamental design for a snowmobile tool, as shown and described.
